UNITED STATES PATENT OFFICE.

EDWIN T. GREENFIELD, OF NEW YORK, N. Y., ASSIGNOR OF ONE-HALF TO
CHARLES J. KINTNER, OF SAME PLACE.

SAFETY-PIN.

SPECIFICATION forming part of Letters Patent No. 587,306, dated August 3, 1897.

Application filed December 31, 1894. Serial No. 533,437. (No model.)

To all whom it may concern:

Be it known that I, EDWIN T. GREENFIELD, a citizen of the United States, residing at New York, in the county of New York and State of New York, have made a new and useful Invention 5 in Safety-Pins, of which the following is a specification.

My invention has for its object the production of a safety-pin which shall be cheap of 10 construction, simple and efficient, and will remain securely locked when once placed in closed or connected position in the material to be pinned or fastened; and to this end it 15 consists in the novel form of pin hereinafter described, and particularly pointed out in the claims at the end of this specification.

Figure 1 of the drawings represents a side elevational view of my improved safety-pin in closed or connected position. Fig. 2 is a 20 similar side elevational view of the same in open or disconnected position. Fig. 3 is a similar side elevational view of my invention provided with means for more firmly locking the parts of the pin together.

25 I take a single piece of steel wire of the desired length and coil it upon itself so as to form a single coil *c* at its middle, which coil through its resiliency causes the pointed or pin part *p* to assume the position shown in 30 Fig. 2. I then coil one end of the wire into a second coil *c'*, of approximately the same size as the coil *c*, leaving a sufficient end to complete a third coil *c²*, the axis of which is normally substantially parallel to the lineal 35 body portion of the pin joining the two coils *c c'*. This coil *c²* acts to sustain and protect the point *p* when in connected or locked position, as shown in Fig. 1. The coil *c* acts as a hinge between the body portion of the pin 40 and the pin proper, while the coil *c'* acts as a similar hinge between the end of the body portion of the pin and the locking or protecting coil *c²*.

45 For the purpose of rendering the pin more secure when the parts are locked together in the manner shown in Fig. 1 I sometimes bend the end of the pin *p* in such manner that when stress is put upon the side parts *w w* it will cause the bent point or end to enter between 50 the individual wires of the coil *c²*, thus pre-

venting the point from being drawn out of its surrounding coil. The same effect also might be produced by one or more slightly-barbed points located near the end of the pin where it bears upon the inner face of the 55 coil *c²*. The manner of thus locking the parts together is clearly illustrated in Fig. 3 of the drawings.

In using the pin the operator takes hold of the coil *c* with the forefinger and thumb of 60 one hand and inserts the point *p* through the material to be fastened. He then takes the coil *c²* between the thumb and first finger of the other hand and bends it outward against the resiliency of the coil *c'*. Finally, bringing 65 the two parts together, he releases his hold upon the coil *c²*, so as to allow the point *p* of the pin to enter said coil *c²*, as shown in Fig. 1.

70 By making the coil *c'* to approximate the diameter of the coil *c* it will have a frictional bearing between the cloth or other material to be held and the outer portion of the pin, thereby giving greater security and insuring the permanent locking of the parts together when in position.

75 Having thus described my invention, what I claim, and desire to secure by Letters Patent of the United States, is—

1. A safety-pin composed of a single piece of wire coiled upon itself in three coils, two 80 of said coils lying in substantially the same plane as the body portion of the pin, the third coil having its axis substantially parallel with the body of the pin, the second coil being of such diameter as to act frictionally against 85 the material and hold it firmly against the removable portion of the pin, substantially as shown and described.

2. A safety-pin composed of a single piece of wire having two coils located substantially 90 in the same plane as the body and movable portions of the pin, and a third coil the axis of which is parallel to that portion of the pin which joins the first-named coils, the movable portion of the pin being provided with 95 a holding device and a bent end, substantially as shown and described.

3. A safety-pin composed of a single piece of wire having three coils, one of which acts to separate the parts of the pin, another to 100

lock the parts together and constitute a holding and safety attachment for the point, and another to hold the latter coil in locked position, the point of the pin being provided with means for locking it between the coils of the holding and safety attachment.

5 In testimony whereof I have hereunto sub-

scribed my name this 29th day of December, 1894.

EDWIN T. GREENFIELD.
